FRANK E. COVEY, OF OAKLAND, CALIFORNIA, ASSIGNOR OF ONE-HALF TO CHARLES W. YOLLAND, OF BERKELEY, CALIFORNIA.

CAR-TROLLEY.

1,082,799.

Specification of Letters Patent.

Patented Dec. 30, 1913.

Application filed June 17, 1912. Serial No. 704,076.

To all whom it may concern:

Be it known that I, FRANK E. COVEY, a citizen of the United States, residing at Oakland, in the county of Alameda and State of California, have invented new and useful Improvements in Car-Trolleys, of which the following is a specification.

This invention relates to trolleys for electric railways, and particularly to an automatically reversible trolley.

The object of the present invention is to provide an efficient and practical trolley and collecting wheel for use on high speed and other railway systems involving an overhead trolley line.

It is a particular object to provide a trolley designed to obviate the necessity of manually swinging or reversing the trolley pole when the direction of travel of the car is to be reversed.

A further object of this invention is to provide a trolley involving a single, telescopic trolley pole connected by counterbalancing springs, and which pole is provided with a collecting wheel longitudinally shiftable relative to the pole to compensate for curvatures in the line and such other forces as tend to swing the pole laterally.

The invention consists in a telescopic, spring actuated and counterbalanced oscillating pole with a laterally shiftable current collecting wheel designed to automatically and safely shift at branching lines without danger of jumping.

It also comprises details of construction which will be more fully explained by reference to the accompanying drawings, in which—

Figure 1 is a perspective view of the improved trolley partly broken away. Fig. 2 is a detail, sectional view of the laterally shiftable collecting wheel with the contact blade. Fig. 3 is a cross section on line X—X, Fig. 2.

In its illustrated form, the invention comprises a pedestal or base 2, which may be bolted or otherwise suitably fastened to the deck of a car or other structure on which it may be desirable to mount the trolley.

The base 2 is provided with two cam surfaces 3, whose high points and low points are diametrically opposite each other. Resting upon the cam surfaces 3 are rollers 4 journalized in a swinging chair 5, the vertical hub 6 of which is centrally chambered

so as to embrace and oscillate about a substantial spindle or journal 7 on the base 2.

The upper end of the chair hub 6 is provided with a pivot 8, upon which is pivoted to swing in the plane of arms 9 of the chair a lower tubular pole section 10, to which may be appropriately connected diametrically opposite arms 11. The ends of the arms 11 are perforated, as at 12, to receive opposed tension springs 13, the ends of which are secured in eyes 14 formed in a common plane in the ends of the arms 9 of the chair 5.

The function of the tension springs 13 is to normally maintain the trolley pole section or socket member 10 in approximately a vertical position; the springs each exerting a tension when the pole section 10 is oscillated about its fulcrum 8. Since the eyes 12 of the pole arms 11 and the eyes 14 of the chair arms 9 are designed to be in a uniform plane, it is manifest that when the pole section 10 oscillates, one of the arms 11 moves below the fulcrum 8 tensioning its respective spring, while the opposite arm 11 swings upwardly likewise tensioning its respective spring, the combined force of which springs is effective to bring the pole to a vertical position.

Within the socket section 10 of the pole is provided a substantial expansile spring or other suitable equivalent 15, upon which rests the upper section or end 16 of the trolley pole which is normally forced upwardly by the expansile spring 15 so as to carry a collecting spool or wheel 17 with sufficient force against the trolley line 18 to make an effective electrical contact. The spool 17 is freely shiftable longitudinally upon an axis or shaft 19, which is suitably secured in bearings 20 at the ends of a yoke or cross-head 21; the latter being rigidly secured to the upper end of a plunger or telescopic section 16 of the trolley pole.

When the pole stands clear in a vertical position, the upward movement of the plunger 16 due to the force of its spring is limited by a pin or other suitable stop 22 engaging a collar or end shoulder 23 of a slot or recess 24 formed in the pivoted pole section 10.

When the collecting spool 17 is to be placed against the trolley wire 18, the operator pulls on a retrieving rope 25. The rope 25 is led downwardly to a convenient

position and runs over a guide or pulley 26, mounted adjacent to the upper end of the pole plunger or section 16; the rope thence continuing down the opposite side of the pole and being fastened, as at 27, to the pivoted section 10. A pull on the rope 25 telescopes the plunger section 16 pressing the cushion or spring 15 sufficiently to enable the operator to swing the collecting spool 17 beneath the trolley wire 18. Then the release of tension on the rope 25 permits the spring 15 to project the spool-carrying plunger 16, and thereafter the contact of the spool will be maintained against the trolley wire 18.

Another purpose of the rope 25 is to enable the operator to pull the spool 17 from engagement with the wire 18, compressing the cushion 15 on which the plunger 16 rests, and also if sufficient force is applied to the rope 25 to oscillate the pole member 10 on its fulcrum 8, as would be the case when it was necessary to run the car or other structure around or beneath or past some obstruction necessitating the lowering of the spool 17 and also the lowering of the pivoted pole section 10.

The purpose of the cams 3 is to automatically maintain the chair 5 in the direction of the line of travel of the car, and if for any reason, as by the manipulation of the pole by the lanyard 25 by the operator, the chair 5 would swing about its vertical pivot 7, and then as soon as the operator released the lanyard the pole and chair would naturally and automatically gravitate to the diametrically opposite low portion between the inclined surfaces of the cams, thus linearly adjusting the chair with the direction of the line of travel.

An important purpose of the longitudinally movable collecting spool 17 is to permit the running of the car at high speed without danger of the spool jumping the trolley due to curvatures in the line of travel and consequently any deflections in the trolley line 18 and also to prevent the trolley spool from jumping when the car is rolling. Since the collecting spool 17 may move freely, laterally, of the trolley pole 10-16, it will be manifest that there will be substantially no lateral strain put upon the pole, for the reason that the trolley collecting spool or wheel 17 will automatically shift to one side or the other to compensate for deviations in the line of travel and to compensate for the lateral swinging of the deck of the car and the trolley pole when the car is rolling. For instance, assuming that the car is running in a straightaway course for a given distance and the cable 18 is deflected angularly, as at switches, curves, etc., then the trolley collecting wheel 17 will automatically shift along its support 19 without subjecting the pole sections 10-16

to any material lateral pressure. From this it will be seen that the car may be run around curves or take switches at a rate of speed which would be impossible with the ordinary narrow, non-shiftable collecting wheel. At the same time the present construction not only permits of high speed operation due to the free lateral shifting of the spool 17, but also eliminates the use of a comparatively long rotary cylinder and its expensive mountings used on high speed train systems.

In order to insure an effective electrical contact between the several members so that the full conductivity of the parts may be obtained, I have shown the spool support or shaft 19 as slotted along one side, as at 28. Freely movable within the slot and projecting into the support 19 is a contact blade 29 of highly conductive properties, which by force of gravitation or otherwise bears upon the interior journaling surfaces 29' of the trolley spool 17, which forces the blade 29 into effective electrical contact with the sides of the slot 28, thus insuring a transmission of current from the spool through the contact blade 29 to the conducting support 19 by which it is transmitted to the conductors formed by or with the yoke 21. This provision is made in order to insure electrical contact between the elements and to avoid the danger of loss of transmission due to lubricating material tending to collect in the running joints which would effectively reduce the transmission.

One of the important provisions of the present invention is means which will enable the collecting spool 17 to automatically clear itself from frogs and switches in the trolley wire connections. This means consists in the present case of forming on the ends of the spool 17 tapering points 30, sufficiently spaced apart to permit the clearance of branch wires between the points 30; yet the points are sufficiently closely arranged to form a substantially peripheral flange at each end of the spool to prevent the latter from moving endwise off of the spool.

The operation of the clearance prongs of the spool 17 is as follows: Assuming that a branch is encountered in the trolley wire 18, when the body of the car takes the switch beneath the branch of the trolley wires the tendency of the yoke 21 is to carry the spool 17 in the direction of the travel of the car, and while the spool 17 may automatically shift to follow the direct line of the cable 18 when the spool has encountered its limit of movement endwise by one of the bearings 21, then as the car moves angularly, the force of the yoke 21 will cause the trolley spool 17 to be carried bodily with the pole. As the branch or crotch of the wires traverses the periphery of the spool, one of the wires will pass between

the prongs 30 while the branch of the wire which is being followed by the car will remain in operative engagement with the trolley spool.

5 When the car upon which the trolley may be mounted is traveling in one direction, the inclination of the trolley pole will be upwardly and rearwardly away from the direction of travel of the car. As the car 10 stops and when its direction of travel is reversed, the telescopic plunger will recede in the socket section of the pole and allow the trolley spool to pass vertically from the center of the chair until the pole assumes 15 an angle opposite to that which it attained previous to the reversal of direction of movement of the car. This is a manifest advantage in trolley constructions especially 20 of a single pole trolley for it obviates the requirement of manual adjustment of the trolley pole when the direction of the travel of the car is to be reversed.

Having thus described my invention, what I claim and desire to secure by Letters Patent is—

1. The combination with a trolley pole, of a chair upon which the pole is pivoted, means connected to the chair for normally maintaining the pole in a vertical position, a trolley wheel mounted upon the upper end of the pole, and a base upon which said chair may turn having cams for normally maintaining the chair in the direction of the line of travel.
- 30 2. In an electric trolley, a carrier turnable about a vertical axis for a distance on each side of a center line, a pole pivotally connected to said carrier for inclination op-

positely in a common plane from a vertical position, tension springs connected at their outer ends to the carrier and at their inner ends to the lower part of the pole and in the horizontal plane of its pivot, said springs acting in opposition to press the pole toward the vertical from either inclination, 45 and a fixed base upon which the carrier is mounted and having means for automatically maintaining said carrier and pole so that the tilting plane of the latter is in the line of travel.

3. In an electric trolley, a carrier turnable about a vertical axis for a distance on each side of a center line, an extensible, telescopic pole pivotally connected to said carrier for inclination oppositely in a common 55 plane from the vertical, tension springs connected at their outer ends to the carrier and at their inner ends to the lower part of the pole and in the horizontal plane of its pivot, said springs acting in opposition to press 60 the pole toward the vertical from either inclination, a fixed base upon the carrier mounted and having means for automatically maintaining carrier and pole so that the tilting plane of the latter is in the line 65 of travel, and means consisting of a slideable wheel on the pole for relieving the carrier and its pole pivot of tilting strains when a turn in a trolley wire is encountered.

In testimony whereof I have hereunto set 70 my hand in the presence of two subscribing witnesses.

FRANK E. COVEY.
